UNITED STATES PATENT OFFICE.

GEORGE M. WELLS, OF MONTCLAIR, NEW JERSEY.

APPARATUS FOR PREPARING REFUSE FOR INCINERATION.

Application filed October 6, 1922 Serial No. 592,678.

My invention relates to an apparatus for preparing refuse for incineration and is particularly useful in the incineration of refuse such as the ordinary house refuse of cities which consists of material of widely varying character and of widely varying sizes and degrees of inflammability. My improved method and apparatus aims particularly to secure a relatively uniform combustion of refuse of this character and to cause its incineration under a forced draft in a closed incinerating furnace.

In the operation of a furnace for incinerating refuse such as above described, measured quantities of refuse are delivered to the furnace and measured quantities of slag or ashes withdrawn, so as to maintain the combustion level in the furnace substantially constant. This operation is quite impossible with ordinary house refuse, particularly if such refuse contain relatively large bodies of readily combustible material which would be apt to form voids in the fuel of the furnace and lead to an unequal distribution of the flame throughout the mass. My improved method and apparatus enables refuse of this character to be handled in an efficient and economical manner.

Referring to the drawings, I have shown:

In Figure 1, a side view, partially in section, of an installation containing my improved apparatus and operating according to my method;

In Figures 2 and 4, a detail of the spreader used in the refuse bin;

In Figure 3, a detail of the doors used in connection with the refuse bin;

In Figures 5 and 6, a plan view and an elevation respectively of the crusher used in the preliminary treatment of the refuse.

Referring to the drawings, an installation using my improved method and apparatus may comprise a landing platform 1, having arranged in conjunction therewith a hopper 2, preferably so located with respect to the platform that vehicles arriving upon the platform may dump from either their sides or their ends into the hopper. Located in the base of the hopper is a crusher which may be driven from the pulley 3, or any convenient source of power, which crusher comprises a pair of toothed rolls 4 and 5, which may be rotated in opposite directions, preferably at different speeds. Said rolls are arranged to be held in position by means of springs 6, or other suitable means for exerting a yielding pressure on the rolls to enable

them to separate without damage to the machine in the event of their encountering a hard object of considerable size incapable of being broken up by the roll. The action of the crusher breaks up the refuse into parts of a relatively small and substantially uniform size and mills or mixes the refuse so that when delivered by the crusher it has a much more uniform composition than when it arrives at the plant and the highly inflammable portions are more or less uniformly distributed throughout the mass.

The crusher discharges into a bin 7, in which is arranged a leveling apparatus which may take the form of a carriage 8, mounted upon wheels 9, adapted to run on tracks 10, supported on supports 11 at each side of the bin. The carriage 8 may be conveniently made of a pair of channel members 12-12 set back to back and having interposed between them a depending scraper 13, the channels being separated and having the wheels 9 mounted on the ends thereof, as illustrated in Fig. 4.

The scraper is propelled along the track 10 by any suitable source of power, and tends to distribute the refuse which, as stated above, has previously been divided into parts of relatively small and substantially uniform size, the leveling operation being illustrated in Fig. 2. The discharging of the refuse into the bin and its distribution by means of the scraper causes a further mixing of the refuse and results in greater uniformity. Furthermore by means of the scraper the bin may be filled to its maximum capacity.

The bin 7 is preferably raised somewhat above the general level of the floor by means of supports 14, or in any other convenient manner, so as to enable the cans 15, or other suitable containers of a standard design and uniform size to be put underneath the bin. Located at the lower edge of the bin are a pair of cooperating doors, shown in detail in Fig. 3 being a perspective view looking upward toward the bottom of the bin. These doors comprise a vertically operating door 16, and a horizontally operating door 17, which join at the edge of the bin. The door 16 may be operated on tracks 18 by means of suitable levers and links 19, the weight of the door being preferably balanced by a counter-weight 20. A similar system of levers is used for the operation of the horizontally moved door 17, but in this case the counter-weight is obviously unnecessary. The arrangement is such

that the operator may open one or both of the doors, thus enabling him to easily and quickly remove the refuse from the bin and fill the containers 15. It will be noted that 5 since the refuse is supplied to the bin at the top and withdrawn from the bottom that the refuse withdrawn has never remained in the bin more than a relatively short time. Where odors have to be avoided as is the case with 10 readily decomposable material such as house refuse, it is important that the refuse be kept in the plant the shortest possible length of time. Furthermore the elevation of the bin above the general floor level permits the liquids contained in the refuse to draw off, thus 15 greatly decreasing the amount of heat necessary to be applied to cause incineration. The location of the doors on the bottom and the sides permits the operator to loosen the refuse 20 by inserting a suitable tool through the vertical door, although due to the previous crushing of the refuse, arching in the bin is greatly reduced.

The containers 15 are then rolled, as by 25 means of a truck beneath the traveling crane 21 and raised to the incinerator platform 22, passing over the rollers 23 to the charging carriage 24. This carriage is arranged to invert the container dumping the charge of 30 the furnace without permitting the escape of furnace gases.

While I have shown and described the preferred embodiments of the present invention, it is, of course, to be understood that various 35 changes in the form and proportions of the device may be made within the scope of the appended claims, without departing from the spirit of the invention.

What I claim is:

1. In an incinerating apparatus, an open 40 top bin supported elevated with relation to a floor plane and having side and end walls forming an upwardly extending refuse chamber with openings through the lower corners of the bin, tracks mounted inset on the side 45 walls adjacent to the open top of the bin, and a removable carriage travelling the tracks and having a dependent scraper cross-wise of the chamber and substantially the width thereof.

2. In an incinerating apparatus, an open 50 top bin supported elevated with relation to a floor plane, and having a relatively wide, substantially horizontal bottom wall and substantially vertical side walls forming with 55 said bottom an upwardly extending refuse chamber, a corner of said side and bottom walls having an opening for withdrawal of the refuse.

3. In an incinerating apparatus, an open 60 top bin supported elevated with relation to a floor plane, and having a relatively wide, substantially horizontal bottom wall and substantially vertical side walls forming with 65 said bottom an upwardly extending refuse chamber, a corner of said side and bottom walls having an opening for withdrawal of the refuse, and opposed closures working toward and away from each other at said corner opening and arranged substantially in 70 the respective planes of the bottom and side walls.

In testimony whereof, I have signed my name to this specification this 5th day of October, 1922.

GEO. M. WELLS.
